UNITED STATES PATENT OFFICE.

GEORGE H. CORLISS, OF PROVIDENCE, RHODE ISLAND.

IMPROVEMENT IN EXHAUST-VALVE GEARS.

Specification forming part of Letters Patent No. 177,099, dated May 9, 1876; application filed January 10, 1876.

To all whom it may concern:

Be it known that I, GEORGE H. CORLISS, of Providence, in the State of Rhode Island, have invented certain Improvements relating to Exhaust-Valve Gear for Steam-Engines, of which the following is a specification:

I use the word valve-gear in the sense in which it is generally used by engineering writers to mean the mechanism of rods, links, rock-shafts, &c., which contribute to impart motion, or to control the motion of valves. My invention is intended more particularly for use with the valves sliding on cylindrical seats, but it may be adapted to other styles of valves.

I will describe it as applied to valves which are operated by being turned a quarter revolution, more or less. Such valve (not represented) when standing in one position forms a free communication through which the exhaust steam may be discharged from the cylinder into the condenser or into the atmosphere. When turned to the other extreme position it tightly closes the corresponding exhaust-port.

It is necessary that for about half the time the exhaust-port shall be either partially or entirely open. When the port is partially open the steam is liable to be "wire-drawn" through such partial opening; therefore it is desirable that the opening and closing movement shall be effected as rapidly as practicable.

In the construction of large classes of steam-engines this fact is appreciated, and the valves are opened and closed by cams in order to effect the motion suddenly. In view of the advantages in the employment of smoothly-working eccentrics rather than cams, I have devised means whereby I can realize a close approximation to the sudden cam movement while deriving the motion from eccentrics.

The following is a description of what I consider the best means of carrying out my invention as applied to an engine in which the exhaust-valves are operated by oscillating-shafts which extend out through stuffing-boxes in the side of the exhaust-chests.

The accompanying drawings form a part of this specification.

Figures 1 and 2 are side elevations, each showing the same portion of the cylinder and exhaust-valve chests of a horizontal engine. Fig. 3 is a diagram showing the peculiarities.

Similar letters of reference indicate corresponding parts in all the figures.

There are two exhaust-valves (not represented) lying at or near the level of the lower side of the cylinder A. Each is equipped with a stem, B, having a rigid lateral arm, B'. The valve is controlled by acting upon the extremity of this arm by means of a suitable link.

I mount near the sweep of that arm a rocking lever, and I link the end of the valve-arm to one arm thereof by a link, C. Now, a vibratory motion given to my said lever by any means—as, for example, by means of a direct connection with an eccentric—will give to the valve a quicker movement near the middle and a slower near each end of each movement, by virtue of the positions assumed by the link C and the different relations which the arms and their motions sustain to each other at different periods. Near the middle of each movement of the exhaust-valve, while the valve-port is opening or closing, the connecting-link C works at a very acute angle to the arm B' on the valve-shaft B, while toward both extremes of its movement it works nearly at right angles thereto. In the position where the valve is only partially open, a little movement of the eccentric induces a great movement of the valve. But at and near each end of the motion the link stands nearly at right angles to the valve-arm or valve-lever B', and oblique to the arm D² of the rocker-lever D. In that position a given amount of motion of the eccentric induces a very much smaller movement of the valve.

In practice I employ a further rocking part, M, which communicates the motion to both valves.

The arrangement is very fully shown in the figures.

The dotted arcs in Fig. 2 indicate the extent of the travel.

E is a rod or link connected to the respective arm D¹, and communicating motion thereto from the pin e, carried on the rocking-wheel M, which latter receives the ordinary oscil-

lating motion by means of a connection, N, to an eccentric (not represented.) The motions of the links E, and, consequently, the vibrations of the levers D¹ D², are modified by the positions of the pins e in the rocking-wheel M.

At each oscillation of the rocking-lever M, the links or rods E are reciprocated. The motion is the familiar one, slow near each end of the movement and considerably faster in the middle part of its movement in both directions. But in order to open and close the valves quickly it is desirable that the movement of the valves shall have these qualities in a much higher degree.

The links E by their reciprocation communicate a corresponding moderate oscillating motion to each lever D¹ D², and each arm D² has a corresponding motion to an extent indicated by the dotted line struck from the center d, and passing near the stem B of the corresponding valve. When the valve is turned to its fullest extent in one direction, all the parts are in the position to which they are approaching in Fig. 1. When the valve is at midthrow, all the parts are in the position shown in Fig. 2. In this midthrow position the link C stands at about right angles to the moderately-oscillating arm D², from which it receives motion, but stands quite obliquely to the arm B', to which it is communicating motion. By reason of its position it has the effect to induce a more rapid motion of the arm B' at the middle of its throw. At each end of its throw, the relation of the arms to each other, and of the link to both, has become so changed that a great amount of motion of the arm D² is required to induce a small motion of the arm B'.

The resulting motion of the valve has been already explained. The valve changes from its closed to its open position almost instantly, and it again changes as rapidly to the closed position.

Various modifications may be made in some of the details. Thus, for example, the rocking shaft or wheel M may be dispensed with,

and the rods E may be connected directly to eccentrics on the shaft, the levers D¹ D² being bent or straightened to correspond with any change of inclination of the rods E. The effect may be heightened by lengthening the arms B' D² and the link C, while the position of the shaft B and the stud d remains the same. This modification, by bringing the arc of motion of the arm D² nearer to the center of the axis of the valve, increases the obliquity of the position at midthrow, and thus induces a more marked effect. If desired in any case, the effect may be still further increased by employing two, or even, it is theoretically possible to use, three or a larger number of levers analogous to D¹ D² and of links analogous to C, playing one into another.

In the diagram, Fig. 3, the relative motion of the several parts near the middle of each movement is indicated by a shaded space, and the relative motion of each part near the end of each movement is indicated by the areas outside of the shaded space, but within the dotted sections.

I claim as my improvement in exhaust-valve motions for steam engines—

1. In combination with the shaft B and arm B', giving motion to an exhaust-valve, the moderately-oscillating arm D², describing an arc near the shaft B, and the link C connecting the arms B' and D², all combined and arranged for joint operation, as and for the purposes herein specified.

2. The levers D¹ D², link C, and arms B' on the respective valve-shafts, in combination with the rocking-piece M and links E therefrom, communicating motion to both sets, as specified.

In testimony whereof I have hereunto set my hand this 6th day of October, 1875, in the presence of two subscribing witnesses.

GEO. H. CORLISS.
